UNITED STATES PATENT OFFICE.

HENRY WIENER, OF NEW YORK, N. Y., ASSIGNOR, BY MESNE ASSIGNMENTS, TO WHITING & DAVIS COMPANY, OF PLAINVILLE, MASSACHUSETTS, A CORPORATION OF MASSACHUSETTS.

HAND BAG.

1,407,310.

Specification of Letters Patent. Patented Feb. 21, 1922.

Application filed October 12, 1920. Serial No. 416,430.

To all whom it may concern:

Be it known that I, HENRY WIENER, a citizen of the United States, residing at New York, in the county of New York, State of New York, have invented certain new and useful Improvements in Hand Bags; and I do hereby declare the following to be a full, clear, and exact description of the invention, such as will enable others skilled in the art to which it appertains to make and use the same.

This invention relates to hand bags, particularly mesh bags of the type extensively used by women for carrying coins and other small articles. Such bags are often times provided with toilet accessories such as a powder box, powder puff and mirror.

This invention is directed to the provision of a bag of this character having a novel form of receptacle for such toilet accessories which is neat, durable and convenient to use and of pleasing appearance.

In accordance with the invention, the receptacle is set into one of the members of the frame of the bag where it may be securely and permanently mounted, where it is accessible and convenient for use and protected from contact with external objects, and where it may be made to harmonize with its supporting frame to produce an artistic, ornamental and graceful article.

Preferably one of the frame members has two side portions which converge upwardly; the metal of the frame member is enlarged between or about the upper ends of these side portions and provided with an opening in which the receptacle proper is secured, the top of the receptacle being substantially flush with the surface of the frame member and the bottom of the receptacle projecting into the bag and toward the mesh or fabric at the other side. Such a bag is usually of rather small thickness when closed and it is important that the bottom of the receptacle shall not cause an unsightly bulge of the mesh which lies close to it, particularly as the mesh where it is so bulged out would soon be injured by contact with external objects. For this reason, the receptacle is made quite shallow and is shallower at its upper edge than at its lower edge, as this shape of the bottom of the receptacle aids in avoiding any bulge in the mesh extending over the bottom of the re-

ceptacle and permits of employing a more attractive design than if the frame member opposite the one carrying the receptacle is solid over the portion which is adjacent to the bottom of the receptacle when the bag is closed.

The receptacle is provided with a hinged cover which opens outwardly and upwardly and the under side of this cover is preferably provided with a mirror. The cover is arranged to be opened by a spring when unlatched and an abutment is provided for limiting the amount of the opening movement. A simple and durable form of spring latch for the cover may consist of a curved resilient arm partially surrounding the receptacle and having a latching tongue at one end which projects into the receptacle in position to engage the cover and hold it in the closed position.

The preferred embodiment of the invention is illustrated in the accompanying drawings, in which Fig. 1 is a front view of a hand bag constructed in accordance with this invention; Fig. 2 is an enlarged section taken on line 2-2 of Fig. 1; Fig. 3 is a detail of the latching spring mounted in position; Fig. 4 is a view of the latching spring itself; Fig. 5 is a view similar to Fig. 1 showing the receptacle open; Fig. 6 is a sectional view on an enlarged scale showing the receptacle open and also showing a detail of the mirror mounting; and Fig. 7 shows a further detail of the mirror mounting.

Referring to the drawings, the hand bag comprises the frame-members 1 and 2 hinged together at 3, and provided with the usual latch 4 and handle 5. The fabric or mesh of the bag is indicated at 6.

The space between the upper part of the sides of frame member 1 is bridged by a portion 7, here shown as a solid portion, but which could evidently be in openwork if desired. A powder box or other outwardly opening receptacle 8 is mounted in the bridging portion 7; the receptacle 8 is preferably circular. This receptacle projects inwardly of the bag, and is held in place by any desired means, usually by soldering. As shown in Fig. 2, the depth of the receptacle at its upper edge is about equal to the thickness of the bag when closed; that is to say, its depth is about equal to the distance from

2
the outside of the frame-member 1 to the outside of the frame-member 2. Of course, this depth may be varied, that is to say, it may be somewhat less or somewhat greater than the thickness of the bag, or about equal to it. It is important, however, that the depth of the receptacle at its upper part, indicated at 9, be such that when the bag is closed, the upper outer edge of the receptacle, indicated at 10, does not cause an unsightly bulge of the fabric 6 of the other side of the bag. Such a bulge or ridge would present an edge which would contact with external objects and be continually subject to wear, and such a bulge would also cause undue strain on the attachment of the mesh just above the receptacle, at the point 11. The thickness of the receptacle 8 at its upper portion should be such that when the bag is closed the mesh hangs in a substantially straight line from its upper attachment over the receptacle and downwardly. Inasmuch as the normal lay of the mesh is at somewhat of an angle, as is apparent in Fig. 2, the lower part of the receptacle 8 may be made deeper, and this is the preferred construction.

Hinged to the portion 7 of the bag is an outwardly and upwardly opening cover 12, the hinge being indicated at 13. Associated with the hinge 13 is a spring 14 so arranged that it causes the cover to open outwardly and upwardly to the position shown in dotted lines in Fig. 2. The extent of this opening movement is limited by an abutment 15 carried by the cover and formed as a part of one of the hinge elements. The cover may open sideways or downwardly, but the upward opening is preferred. The receptacle may also be arranged to face inwardly of the bag, instead of outwardly, as shown in which event the bag would be unlatched before the powder box becomes accessible.

On the inside of the cover is mounted a small mirror 16, preferably a convex one to give a larger field of vision. The mirror mounting, a rear view of which is shown in Fig. 7, comprises a bezel ring 17 provided with inturned lugs 18 that hold the mirror in place. This bezel ring 17 is held in the mirror 12 by a frictional fit, as shown in Fig. 6. The bezel ring is cut away at the point 19.

The spring latch comprises a curved spring arm 20, which extends part way round the receptacle 8. On one end it is provided with a lug 21 which hooks into an aperture 22 cut in the receptacle 8. The other end is provided with a latching tongue 23, which projects into the receptacle and engages with the cover to hold it in latched position. This tongue passes through the receptacle and into an aperture 24 in the cover 12, which aperture registers with the

aperture 19 in the mirror mounting, so that the latching tongue will not interfere with that mounting. In order to operate the latch, there is provided a pin 25 attached to the lower end of the spring arm 20, which projects to the outside of the bag and terminates in a ring 26, to which is attached the finger operated pull tab 27. A slot 28 is provided to allow for movement of the pin 25.

When the cover is closed, a downward pull on the tab 27 unlatches the cover, whereupon it opens to the position shown in Figs. 2 and 6. The spring holds the cover in its open position, and a slight tilting of the whole bag by the user puts both the receptacle 8 and the mirror in a convenient position for use. After use, the cover may be pressed shut, and is automatically latched by the spring latch 20.

45 I claim:

1. A handbag provided with an outwardly opening receptacle mounted in the framework of the bag, a hinged cover for said receptacle and latching means for said cover, comprising a resilient arm engaging the receptacle at one end and curved to partly encircle the receptacle, and provided with a latching tongue adapted to engage the cover at the other end.

2. A handbag comprising a pair of hinged frame members which converge upwardly, a bridging portion extending across the space between the sides of one of the frame members, fabric for completing the bag carried by the frame members, and an outwardly opening receptacle provided with a hinged cover mounted in said bridging portion, the receptacle extending into contact with the fabric carried by the other frame member and being made shallower at the top than at the bottom so as not to cause a bulge in said fabric where it contacts therewith.

3. A handbag comprising a pair of hinged frame members, a bridging portion extending across the upper part of the space between the sides of one of the frame members, an outwardly opening receptacle mounted in said bridging portion, a cover for the receptacle, a latch for the cover, spring means for automatically opening the cover when it is unlatched, and an abutment for limiting the opening movement of the cover.

4. A handbag comprising a pair of hinged frame members, a bridging portion extending across the space between the sides of one of the frame members, an outwardly opening receptacle mounted in the bridging portion, a cover for the receptacle, and a mirror on the inside of the cover.

5. A handbag comprising a pair of hinged frame members, a bridging portion extending across the space between the sides of one of the frame members, an outwardly opening receptacle mounted in the bridging por-

tion, a cover for the receptacle, latching means for holding the cover closed and spring means associated with the cover to cause it to fly open when unlatched.

5. 6. A handbag comprising a pair of hinged frame members, a bridging portion extending between the sides of one of the frame

members, an outwardly opening receptacle mounted in the bridging portion, a cover for the receptacle arranged to open upwardly and outwardly, and a mirror on the inside of the cover.

In testimony whereof I affix my signature.
HENRY WIENER.
